SURGICAL DRESSING

Warner Eustis, Newton, Mass., assignor to The
Kendall Company, Walpole, Mass., a corpora-
tion of Massachusetts

Application July 20, 1934, Serial No. 736,177

11 Claims. (Cl. 128—156)

This invention relates to surgical dressings, bandages, and similar products.

A type of dressing much used by the general public consists of a short section of adhesive tape carrying a small medicated pad which usually is located at an intermediate point in the length of the tape and is adhesively fastened to it. Such dressings have been sold heretofore chiefly in packages, each package containing a certain 10 designated number of separate dressings. Since the adhesive coating on the tape is normally tacky, it is necessary to protect it in some way and this is commonly effected by covering the adhesive area with gauze, crinoline, or the like. Recently an improved form for packaging dressings 15 of this type has been devised which consists in attaching a series of separate dressings to a strip of gauze in such a manner that the dressings are supported on and carried by the gauze so that 20 the entire strip can be rolled on to a spool and conveniently enclosed in a suitable wrapper or casing. This arrangement has the advantage of protecting the dressings and presenting them in a form convenient to use, since any individual 25 dressing can readily be stripped off the gauze carrier whenever it is needed.

The present invention aims further to improve and perfect the form in which bandages or dressings of this general character are prepared for 30 re-use with a view to reducing the expense involved in such preparation, providing a construction which will lend itself to manufacture by automatic machinery, preserving the advantages of the improved form of package above described, and facilitating the protection, handling, 35 and use of this type of product.

The nature of the invention will be readily understood from the following description when read in connection with the accompanying drawings, and the novel features will be particularly 40 pointed out in the appended claims.

In the drawing,

Figure 1 is a perspective view of a dressing package embodying features of this invention;

Fig. 2 is a plan view of a portion of the dressing strip illustrated in Fig. 1;

Fig. 3 is an edge view of said strip;

Fig. 4 is a perspective view of one of the dressings and a portion of the protective sheet material associated therewith; and

Fig. 5 is a perspective view illustrating a further embodiment of the invention.

The dressing strip illustrated in the drawing comprises a series of individual dressings, certain of which are indicated at 2, 3 and 4, respec-

tively. Each of these dressings consists of a short length of adhesive tape which, in a typical instance, may be about three inches long, and has a pad P secured to the central portion thereof by the adhesive coating. While the character of the 5 coating may vary substantially, that most commonly used commercially is normally tacky and will adhere either to itself or to a great variety of non-adhesive surfaces. Such tapes are widely used and are well known in this art. The 10 pad P may consist of a small body of gauze, absorbent cotton, or the like, and frequently these pads are impregnated with some germicidal preparation, such as mercuriochrome. As above indicated, dressings of this construction have been 15 on the market for several years.

According to the present invention these dressings are secured together in approximately an end to end relationship by means of relatively short sections of gauze, crinoline, or other sheet material which, in addition to connecting the dressings together, also serve to protect the adhesively coated surfaces of the dressings from contact with other surfaces to which they might 20 adhere. Certain of these gauze sections or strips 25 are indicated at 5, 6, 7 and 8, respectively. Considering for the moment the dressing 3, it will be observed that it is connected to the dressing 2 by the strip 6 of gauze and to the dressing 4 by another strip 7. Also, that practically the entire 30 adhesive surface of the backing strip of the dressing (other than that portion covered by the pad P) is protected by the two strips of gauze, and that these strips operatively connect the dressings 35 by their adhesion to the tacky surfaces of the sections of adhesive tape. Each dressing is similarly connected to its neighbor so that the gauze sections connect the dressings adhesively but separably together to form a continuous strip 40 which may be folded, wound on a roller, or put up in any other convenient manner.

Preferably the ends of each pair of adjacent strips of gauze such, for example, as those shown at 6 and 7, are overlapped upon the pad of the 45 dressing to which both are secured. This arrangement is of advantage in removing any individual dressing from the dressing strip. Usually the endmost dressing is removed whenever one is required. If we assume that it is desired to remove the dressing 2 in Fig. 1, it is simply necessary to strip the gauze 5 off this dressing by grasping the free end 5' of the gauze and pulling it away from the backing strip. Then the free end 6' of the other gauze section 6 may be grasped 55

- and held in the thumb and fingers of one hand while the dressing is similarly grasped in the other hand and pulled away from the gauze, these operations being repeated whenever it is desired to remove any individual dressing. Normally the overlapped ends of the gauze sections lie flat against the surface of the pad which they are to cover, but they have been shown somewhat separated from the pad in the drawings in order to illustrate the construction more clearly.
- When such a dressing strip is wound on a spool or into the form of a roll, it may be protected in any convenient way as, for example, by enclosing it in a box in much the same manner as rolls of surgeon's adhesive tape are commonly sold. Fig. 1 shows such a dressing strip wound on a spool 10, this spool having metal heads over which a sleeve 12 may be snapped to cooperate with the heads in closing and protecting the dressing material.
- A package of this kind preserves all of the more important advantages of the present commercial arrangements for putting up dressings of this general type, such for example, as protecting the dressings from soiling or contamination, facilitating the easy removal of the individual dressings, and the like. In addition, it lends itself readily to manufacture by automatic machinery, it reduces the quantity of gauze or crinoline required by the more recent and better packages, and it holds all of the dressings together in substantially a continuous strip, avoiding any opportunity for the dressings to swing out of line and cause trouble in winding, folding, or the like.
- A further advantage is the fact that any necessity for using a knife or scissors to cut away surplus gauze, or for any other purpose, is avoided. It should also be noted that as the dressings are successively removed from the end of the strip, the length of the strip is correspondingly shortened so that there is never any surplus material in the strip other than possibly the very short end of gauze which may project beyond the extremity of the endmost dressing. Since each dressing is complete in itself, its separation from an adjoining member of the strip does not leave a torn or ragged edge, but all the edges of the dressing are clean.
- These advantages are also obtained in the form of the invention illustrated in Fig. 5 in which the end portion of the tape section of each dressing is overlapped upon a corresponding member of the next adjacent dressing and is thus adhesively but releasably secured to it. Considering any individual dressing, as for example that shown at 3', Fig. 5, it will be observed that its adhesive coating on the end thereof at the left of the pad P is protected by the fact that it overlaps the uncoated or back surface of the tape of the next adjacent dressing 4'. The lower coated surface of the section of tape so overlapped, however, is protected by a strip of gauze, crinoline, or the like g. The corresponding portions of each of the tapes are similarly protected by short additional sections of gauze. Preferably, also, each lower end of the tape overlaps the pad P of the next adjacent dressing and terminates on said pad. Likewise the ends of the gauze sections overlap this pad. Since the surface of the end portion of the tape which comes in contact with the pad is the uncoated surface, it does not adhere to the pad, and by having it overlapped upon the pad in this manner, it is a very easy matter for the user to grasp this free end of tape between the thumb and fingers while

stripping off the end portion of an adjoining dressing. It is for the same reason that the ends of the gauze sections are overlapped upon the pads. In this embodiment of the invention the area of gauze or crinoline required to protect the adhesively coated surfaces is further reduced.

It should be observed that in both of these embodiments of the invention the individual dressings are adhesively connected to form a continuous, self-supporting dressing strip from which an individual dressing may be stripped off, when desired. Since the continuity of the strip depends upon the adhesiveness of portions of the dressings themselves, the strip may be separated at practically any desired point simply by breaking the adhesive union between one of the dressings and the next adjacent element of the strip. This is a convenience when it is desired to remove a series of dressings for any reason.

Having thus described my invention, what I desire to claim as new is:

1. A dressing strip comprising a series of individual dressings, each including a portion coated with an adhesive, and sections of sheet material adhering to and protecting the adhesively coated surfaces of said dressings and connecting said dressings together to form a continuous dressing strip, adjacent sections of said sheet material having end portions overlapping each other upon an intervening dressing to provide free ends which may be grasped to facilitate the removal of the protecting sections from the individual dressings.

2. A dressing strip comprising a series of individual surgical dressings, each including a relatively short section of adhesively coated tape, said sections of tape being overlapped, one upon another, to connect said dressings together in a series relationship, each of said dressings including a pad and the end of the tape of one dressing being overlapped upon the pad of the next adjacent dressing

3. A dressing strip consisting of a series of individual adhesive surgical dressings, each comprising an adhesive tape, a pad secured to the tape and a section of sheet material adhering to and protecting an adhesive surface of said tape, each section of sheet material being of a length to extend from its respective tape into overlapping relation with the absorbent pad on an adjacent tape, said dressings being connected through the medium of the adhesive on the individual dressings to form the dressing strip, the continuity of which depends upon said adhesive, whereby an individual dressing may be pulled off the end of said strip whenever desired by breaking its adhesive union with the strip, thereby shortening the length of said strip as successive dressings are removed.

4. A dressing strip comprising a series of individual adhesive surgical dressings, each including a section of tape coated with a normally tacky adhesive and a pad thereon, and a protective sheet extending over an adhesive surface of one tape into overlapping relation with the pad on an adjacent tape, said dressings being normally maintained by said adhesive on the respective dressings in a series relationship to each other, such that the strip may be parted at the end of an individual dressing by breaking its adhesive union with the next adjacent element of the strip, the end of the protective sheet which overlaps a pad being free from adhesive.

5. A dressing strip comprising a series of indi-

vidual dressings each including a portion coated with an adhesive, a pad, and sections of sheet material adhering to and protecting the adhesive-coated surfaces of said dressings and connecting said dressings together to form a continuous dressing strip, adjacent sections of said sheet material having end portions overlapping each other upon an intervening pad to provide free, non-adhesive ends normally protecting said pad, and which may be grasped to facilitate the removal of the protecting sections from the individual dressings.

6. A dressing strip comprising a series of individual adhesive surgical dressings adhesively united to form a continuous separable self-supporting dressing strip from which an individual dressing may be separated when desired merely by breaking its adhesive union with said strip, and including protective elements each covering portions of the adhesive areas of two adjacent dressings and of a pad in the mid-section of each of said adhesive dressings, said protective element having an end lying freely over said pad so that said end may be grasped for purposes of detaching same from the dressing.

7. A dressing strip comprising a series of surgical dressings each including relatively short sections of adhesively coated sheet material and a series of connecting members adhesively but separably united to said individual dressings, each connecting member being free from said adhesive at both ends.

8. A surgical dressing strip comprising a series of individual adhesive surgical dressings having at both ends of each dressing, portions coated with a pressure-sensitive adhesive, and a series of connective pieces adhering to said adhesive portions of said dressings, each of said connective pieces being free of said adhesive at both ends and each of said connective pieces also serving to hold together two adjacent surgical dressings to form a continuous strip from which individual dressings may be separated.

9. A dressing strip comprising a series of individual adhesive surgical dressings, each dressing including a tape section coated with adhesive,

pads between the ends of said dressings and of such size and so located as to leave adhesive areas uncovered by said pad at both ends of each tape section, pieces of protective sheet material covering one adhesive end of each dressing, the opposite adhesive end of each of said dressings being adhesively attached to the back of the portion of the tape of an adjacent dressing which is covered on the opposite face by one of the aforementioned protective sheets, whereby the strip may be parted at the end of any individual dressing by breaking its adhesive union with the next adjacent dressing and thus to separate such individual dressings from the dressing strip.

10. A dressing strip comprising a series of individual surgical dressings, each including a relatively short section of tape coated with a normally tacky adhesive and having a pad secured to the coated surface of the tape, a portion of the tape of each of said dressings being overlapped upon and adhesively secured to a part of the next adjacent dressing to secure said dressings together in a series relationship to form a dressing strip from which the endmost dressing may at any time be removed by breaking its adhesive union with the next adjacent dressing, and each of said dressings including a strip of sheet material adhering to and protecting part of the coated surface of the tape with an end of said protective strip overlapped on one of said pads.

11. A dressing strip comprising a series of individual surgical dressings, each including a relatively short section of tape coated with a normally tacky adhesive and having a pad secured to the coated surface of the tape, said sections of tape being adhesively overlapped, one upon another, to connect said dressings together in a series relationship to form a dressing strip from which the endmost dressing may at any time be removed by breaking its adhesive union with the next adjacent dressing, each of said dressings including a pad and a protective strip of sheet material on the coated surface of the tape with its end overlapped on the pad but free from it.

WARNER EUSTIS.
